UNITED STATES PATENT OFFICE.

CHARLES J. BENNETT, OF SANTA CRUZ, CALIFORNIA.

COIN-CONTROLLED LOCK.

1,096,671.

Specification of Letters Patent. Patented May 12, 1914.

Application filed October 28, 1912. Serial No. 728,255.

To all whom it may concern:

Be it known that I, CHARLES J. BENNETT, a citizen of the United States, residing at Santa Cruz, in the county of Santa Cruz and State of California, have invented new and useful Improvements in Coin - Controlled Locks, of which the following is a specification.

This invention relates to a mechanism for controlling the operation of a lock and a latch.

The object of the present invention is to provide a substantial, reliable and self-contained coin-controlled locking mechanism embodying a device for preventing the removal of the key from the actuating lock, and which device, through means of the lock, controls the operation of a latch to prevent the opening of a door upon which the self-contained mechanism may be mounted.

The invention consists in the combination of a suitable casing and an appropriate form of lock mounted thereon, with means for preventing the removal of the key from the lock without the insertion of a coin, check, or other token, and in combination with a latch, the movement of which is controlled by the mechanism.

Figure 1 is a rear view of a door with the self-contained and locking mechanism applied. Fig. 2 shows the controlling device in locking and key releasing position. Fig. 3 is a horizontal cross section in the plane of the top of the latch and lever. Fig. 4 is a view showing in perspective detail parts.

In its illustrated embodiment, my invention comprises a suitably shaped panel, stamped casting, or other form of casing member 2, which may be attached in any suitable manner to the door or other structure 3 which it is desired to keep in a locked position, and which may be hingedly connected for movement. The casing may be provided with suitable interlocking devices or projections 4 adapted to automatically lock or register with complementary recesses or pockets 5, formed on the door or structure 3 to which the apparatus is to be applied. The casing member 2 is provided with a coin or other device receiving slot 6 which opens and inclines inwardly and downwardly and is adapted to receive a coin which, if it be of the proper denomination or size, will, during its gravitation through the slot or channel formed for its reception, abut against the engaging shoul-

der 7 of a lever 8. The lever 8 is pivotally fulcrumed, as at 9, on the inside of the lock casing or frame 2; the upper end of the lever being provided with a seat 10 for the engagement of a spring 11, the function of which is to throw the lever in one direction or toward the barrel or other lock body 12. Upon the lock body 12 is mounted a movable cylinder or member 13, adapted to be turned by a key 14, the handle end of which projects outwardly, normally, through the lock casing 2.

The lever 8 is adapted to be oscillated against the restraint of its spring 11 by means of a lug 15, carried by the movable member 13 of the lock 12. When the key 14 is turned, the lug 15 moves into engagement with and may swing the lever about its fulcrum. However, the continued uninterrupted movement of the key, with its associated movable member, in the lock is prevented by the interception of the lug 15 with a pawl 16 also pivoted on the pivot 9; the pawl having a shoulder 17 against which the lug of the lock member 13 will abut during its movement without some means having been introduced for coupling the lever 8 temporarily with the pawl 16.

In the present invention it is contemplated that a sufficient movement of the key and its associated lock member 13 may be had only after a coupler, connector or bridge, as a coin or other desired device indicated at 18, is introduced into the mechanism by insertion through the slot 6 of the panel 2, and which, when introduced and of the right size, will lodge against the intercepting shoulder 7 of the lever and also against the intercepting or engaging shoulder 19 formed on the pawl 16. This pawl, as before stated, has the abutment or stop shoulder 17; this being normally held in the path of the lug 15 of the lock member 13 by the pressure of a spring arm 20 engaging the latch 16. When the proper coin or other connector has been introduced and remains sustained by and between the shoulders 7 of the lever and 19 of the latch, then when the key 14 is forcibly turned, the lug 15 moves into engagement against the contiguous portion of the lever 8. This is bodily rocked about its fulcrum 9; the power applied to the key acting through the lug 15 upon the lever 8, and this in turn pressing against the inserted coin 18 enables the latter, abutting the engaging shoulder 19 of the pawl, to actuate

the pawl 16 to rock simultaneously as if integral with the lever 8. The key 14 is turned by the operator without restraint of the latch, other than from the resistance of the 5 spring 20, until the key is in such position with relation to the lock structure 12 that it is free to be released therefrom or inserted therein.

When a person desires to deposit a parcel 10 or other property in a closet, wardrobe, locker, or whatever the structure may be to which the mechanism is applied, the door or closure 3 is designed to be unlocked when the key 14 is in the lock restraining mechanism, so that free access may be had to the 15 locker, for instance, and after depositing the property in the locker, the party then closes the door 3. By depositing the required coin or device in the mechanism by insertion 20 through the slot 6 a person may turn the key; the coin acting as a coupler or connector between the lever and the pawl and permitting the key-actuated member 13, with the key, to be moved sufficiently to entirely 25 remove the key.

Simultaneously with the movement of the key and its associated lock device a latch bolt 21 mounted on the door or panel 2 will become locked by the upwardly lifted corner 30 or portion 22 of the latch 16, which is so formed as to move into a position behind, or in such relation to the latch bolt 21 as to prevent this from being withdrawn from its keeper, unless the key, as 14, is inserted in 35 the lock 12 and actuated so as to release the latch bolt 21 by the movement or removal of the latch 16.

From the foregoing it will be seen that when the door structure 3, with its attached 40 controlling device 2, is unlocked, the key 14 will be in the lock 12 and restrained against removal therefrom until a coin or other requisite coupler, as 18, has been introduced, so that a party wishing to use the locker or 45 other receptacle may insert property therein, close the door 3, drop a coin in the slot 6, which coin becomes operative as a coupler, and then by turning the key 14 the lever 8 with the latch 16 moves as a whole under the 50 force of the lug 15 turned by the key 14, simultaneously moving the latch bolt stop 22 into such relation with the latch bolt 21 as to lock it against movement to prevent opening of the door. Then the key 14 may be 55 removed and the door can only be opened again by its re-insertion and reverse movement which will allow the springs 11 and 20 to return their co-operative members, as lever 8 and latch 16, to normal position; the latch 60 reassuming its position to stop the swinging movement of the lug 15 of the lock 12, and at the same time releasing the latch bolt 21. Then the door may be opened and the key 14 locked in its co-operative lock 12.

65 Preferably the coin-receiving slot 6 will

be so proportioned and formed as to permit of the insertion of the coin or coupler, as 18, of the right diameter or size. In the event that a smaller sized piece is introduced in the slot 6, this is rejected by the apparatus, 70 as it will fall freely through the oppositely disposed abutment devices or shoulders 7 and 19 and fall through and discharge from an escape slot 24 and will be returned to the depositor. In the event that an over-sized 75 coin or piece is inserted into the device, it will be unable to properly lodge between the receiving shoulders 7 and 19, and when the person attempting to remove the key turns it, the consequent movement of the lever 8 will cause the shoulder 7 to roll the piece introduced over the shoulder 19, whereupon the oversized piece will be rejected and discharged outwardly through a slot or opening 25. When the proper sized piece is introduced and serves its function as a coupler or rigid connector between the lever shoulder 7 and the latch shoulder 19, the piece 80 will be released, when the key is turned a requisite amount to permit its removal, and falls into a collecting drawer or box 26 which is formed on or attached to the casing or panel 2 and to which access may be had by the proprietor of the establishment. 85

Having thus described my invention, what 90 I claim and desire to secure by Letters Patent is—

1. The combination with a bolt, of a pawl normally clear of the bolt and adapted to intercept the same, a key actuated cylinder 100 having a lug for actuating said pawl and a key for said cylinder, said pawl being designed to intercept the lug to prevent removal of the key, and a lever acting in combination with the pawl to sustain a proper coin and engageable by said lug, whereby the pawl may be actuated, when the proper piece is inserted, to intercept the bolt and clear said lug from restraint to permit the removal of the key. 110

2. In a coin-controlled lock, a lock-casing having a coin feed slot, a key cylinder and a key therefor, a lug projecting from the cylinder, a normally projected bolt movable on the casing, a pawl having a shoulder with which said cylinder lug is engageable and having a rest for a proper sized coin insertible in the feed slot, and a lever having a rest and co-operating with the rest on the pawl to sustain said coin when inserted, said lever engaging and coacting with the cylinder lug so that when the cylinder is turned by its key the pawl shoulder is actuated to a position to clear the cylinder lug so that the key can be removed, the coin released, 125 and the bolt intercepted.

3. In a coin-controlled lock, a lock-casing having a coin feed slot and coin return slots, a key cylinder and a key therefor, a lug on the cylinder, a normally projected bolt mov- 130

able on the casing, a pawl having a shoulder with which said cylinder lug is engageable and having a rest for a proper sized coin insertible in the feed slot, and a lever having a 5 rest and coöoperating with the rest on the pawl to sustain said coin when inserted, said lever engaging and coacting with the cylinder lug whereby when the cylinder is turned by its key the pawl shoulder is actuated to a position to clear the cylinder lug so that the key can be removed, the coin

released, and the bolt intercepted, the lever having a stop for restraining the turning movement of said cylinder at a given position.

15

In testimony whereof I have hereunto set my hand in the presence of two subscribing witnesses.

CHARLES J. BENNETT.
